UNITED STATES PATENT OFFICE.

EDWIN G. PICKERING, OF NEAR DAYTON, OHIO.

IDENTIFYING-CARD.

1,246,653.

Specification of Letters Patent. Patented Nov. 13, 1917.

Application filed June 8, 1917. Serial No. 173,481.

To all whom it may concern:

Be it known that I, EDWIN G. PICKERING, a citizen of the United States, residing near Dayton, in the county of Montgomery and 5 State of Ohio, have invented a new and useful Improvement in Identifying-Cards, of which the following is a specification.

This invention relates to a new and useful improvement in identifying cards. 10 The principal object of my invention is to provide an identifying card which, by improved means, may be readily and firmly attached to the coat of the wearer for the purpose of identifying him to his fellows 15 on all occasions.

The preferred form of embodiment of my invention is illustrated in the accompanying drawings, of which Figure 1 is a vertical plan view of my identifying card 20 containing a D-shaped aperture in the upper central portion thereof. Fig. 2 is a side view of the inverted-L shaped element which I employ to fasten the card to the lapel of a coat. Fig. 3 is a front view thereof. Fig. 4 is a plan view of a coat to the lapel of which my identifying card is attached. Fig. 5 is a vertical section taken through said lapel, showing how the card is suspended from the inverted-L shaped element. And Fig. 6 is a vertical plan view 30 of a card containing a slit in its upper central portion.

Throughout the specification and drawings, similar reference characters denote 35 corresponding parts.

In a detailed description of the preferred form of embodiment of my invention, the numeral 1 designates a card preferably rectangular in shape to receive the name of 40 the person to be identified by it, written thereon in a vertical manner.

Provided in the upper central portion of the card 1 is a D-shaped aperture 2 to easily receive the head portion of an inverted-L 45 shaped pin 3. Referring to Figs. 2 and 3, this pin is preferably one whose shank is bent at its upper end to form a right-angled portion which is adapted to project beyond the button-hole of a coat lapel 4 when its

lower end is embedded in the fabric as 50 shown in Fig. 5. This pin has no crank portion, but instead the upper portion of its head is cut away as shown in Figs. 2 and 3. In other words, the head of the pin is 55 so shaped as to be D-shaped in cross-section, to enter the D-shaped aperture 2 in the card 1.

The normal position of the head portion of the pin 3 when not in use, is preferably 60 behind the coat lapel 4 as shown in dotted lines in Fig. 5, thereby being concealed from view. When it is desired to secure the identifying card 1 to the coat lapel 4, the right-angled portion of the pin 3 is given a half turn, whereby its head portion is brought 65 through and beyond the buttonhole, into a position to receive the D-shaped aperture 2 in the card 1. The card 1 is inverted to permit the D-shaped head of the pin, which is slightly smaller than the D-shaped aperture in the card, to be thrust through the latter, whereupon the card is turned to the position shown in Fig. 4. In this position the card will depend from the right-angled portion of the pin, and will be firmly locked 70 thereto by reason of the fact that the corners of the D-shaped head of the pin extend beyond the upper D-shaped portion of the aperture 2 of the card. In other words, when the card has the position shown in 75 Fig. 4, the D-shaped head of the pin will act as a flange against the edge of the D-shaped aperture 2, to firmly and irremovably hold the card on the pin.

If the identifying part 1 is made of very 80 flexible material, it may be provided in its upper central portion with a slit 5 to receive the D-shaped head of the pin 3. (See Fig. 6).

I do not wish to be limited to the details 85 of construction and arrangement herein shown and described, and any changes or modifications may be made therein within the scope of the subjoined claims.

Having described my invention, I claim: 90

1. An identifying card adapted to receive 95 a name written in a vertical manner, and an inverted L-shaped element coöperating with

a D-shaped hole formed in the top portion of said card, for firmly securing it in a vertical position to the coat of the wearer.

2. An identifying card adapted to receive 5 a name written in a vertical manner, and an inverted-L shaped pin having a D-shaped head for coöperation with a D-shaped hole formed in the top portion of said card, for

firmly securing the latter in a vertical position to the coat of the wearer.

10

In testimony whereof I have hereunto set my hand this 7th day of June, 1917.

EDWIN G. PICKERING.
